DESIGN FOR A GAME BOARD

George G. Allenbaugh, Wadsworth, Ohio

Application June 10, 1946, Serial No. 130,569

Term of patent 14 years

(Cl. D34—5)

To all whom it may concern:

Be it known that I, George G. Allenbaugh, a citizen of the United States, residing at Wadsworth, in the county of Medina and State of Ohio, have invented a new, original, and ornamental Design for a Game Board, of which the following is a specification, reference being had to the accompanying drawings forming part thereof and wherein:

I claim:

The ornamental design for a game board, as shown.

GEORGE G. ALLENBAUGH.
